UNITED STATES PATENT OFFICE

ALBERT B. HODGES, OF CHICAGO, ILLINOIS, ASSIGNOR TO GENERAL ZEOLITE COMPANY, OF CHICAGO, ILLINOIS, A CORPORATION OF ILLINOIS

VARIABLE-RATE CHEMICAL FEED PUMP

Application filed September 15, 1928. Serial No. 306,117.

The present invention pertains to pumps of the reciprocating plunger type, and resides in an improvement which when incorporated in such a pump will render the same particularly adaptable for use in those water-softening plants where a pump is needed which will feed the chemical to the water in a constant proportion regardless of fluctuations in the rate of flow of the water.

The reciprocating plunger pumps heretofore used for that purpose have not been entirely satisfactory owing to the fact that it is practically impossible for an operator, even by making frequent adjustments to the pump, to maintain anything like a constant proportion between the rate of flow of the chemical and the rate of flow of the water throughout fluctuations in the latter.

The object of the invention is to provide a novel pump control mechanism which, when used in water softening plants where the rate of flow of the water fluctuates, will automatically vary the rate of flow of the chemical in conformity with variations in the rate of flow of the water.

While the foregoing statements are indicative in a general way of the nature of the invention, other objects and advantages will be evident to those skilled in the art upon a full understanding of the construction, arrangement and operation of the novel pump control mechanism.

One form of the invention is presented herein for the purpose of exemplification, but it will of course be appreciated that the invention is susceptible of embodiment in other structurally modified forms coming equally within the comprehensive scope of the appended claims.

In the accompanying drawings:

Fig. 1 is a side view of a chemical feed pump equipped with the control mechanism of the invention;

Fig. 2 is an end view; and

Fig. 3 is a top view.

The pump shown in the drawings consists of a plunger 10 which reciprocates vertically within a casing 11. On each upstroke of the plunger, a certain quantity of the chemical being fed is drawn into the casing past a

one-way valve 12 in a supply line 13 connected with the bottom of the casing, and, on each downstroke, an equal quantity is forced out of the casing past a one-way valve 14 in a feed line 15 connected with the side of the casing.

The plunger 10 is connected at 16 with a cross head 17 which reciprocates vertically on two spaced guide rods 18. The cross head is caused to move downwardly by a roller 19 which is eccentrically mounted on one end of a rotating shaft 20 and engages at 21 with the cross head, and is caused to move upwardly by two compressed springs 22 which encircle the guide rods and press upwardly against the cross head. The shaft 20 is rotated by an electric motor 23 through suitable reduction gearing located in a housing 24.

The upward movement of the cross head 17 is limited in any one of a number of positions by a cam 25 which engages at 26 with a portion of the cross head which is forwardly offset with respect to the portion with which the roller 19 engages. The cam 25 is secured to one end of a shaft 27 which is journaled in a bracket 28 carried by the guide rods. A pulley 29 is secured to the other end of the shaft 27, and is grooved helically to receive two or more turns of a cable 30. The cable 30 extends from the pulley 29 in one direction over two idling pulleys 31 down to a control float 32 in a tank 33, and extends in the other direction over an idling pulley 34 down to a counterweight 35.

The float 32 is caused, by any means suitable for the purpose, to rise or descend in conformity with any increase or decrease in the rate of flow of the water, and, since the elevation of the float determines the angular position of the cam 25, any change in the rate of flow of the water will cause a corresponding change in the angular position of the cam, resulting in a corresponding change in the length of the stroke of the plunger and a corresponding change in the rate of flow of the chemical through the feed line to the water.

In the particular position of the cam shown in Fig. 2, wherein the shortest radius of the cam is directed toward the cross head, the

plunger of the pump is permitted to take a full stroke. When the cam is rotated in a clockwise direction, by reason of the float lowering, progressively longer radii of the cam are directed toward the cross head, shortening the stroke of the plunger in proportion to the extent to which the cam is rotated in that direction. Should the cam be rotated in that direction to such an extent as to direct the longest radius of the cam toward the cross head, the cross head would be held by the cam against all movement, and, while the roller would continue to revolve as before, there would be no flow from the pump.

Where the float 32 is connected up with the flow of the water in such a way as to cause the vertical movement of the float to be in direct proportion to the change in the rate of flow of the water, the cam will be spirally shaped, as shown in Fig. 2, but, where other hook-ups are employed for the float, the cam will of course have an appropriately changed shape.

In pumps of this type there may be a certain amount of leakage back through the inlet valve on the downstroke of the plunger, or a certain amount of leakage back into the casing from the outlet valve on the upstroke of the plunger, so that the full amount of delivery corresponding to the displacement of the plunger is not attained. This leakage may or may not be proportional to the length of the stroke of the plunger, depending upon the particular pump structure employed.

The construction herein disclosed permits this leakage to be compensated for, if desired, as follows: The cam, instead of being made of such shape as to permit of a stroke exactly corresponding to the flow of the water, may be so shaped as to increase the stroke to correspond both with the increased or decreased flow of the water and the increased or decreased leakage. Thus the radii of the cam may be each increased by a uniform amount, or the radius at one point in the cam may be increased a proportionately different amount than the radius at another point.

A pump embodying the present invention is capable of delivering a stream under pressure, automatically varying the rate of flow, and automatically compensating for pump leakage at different lengths of stroke. Such a pump, while particularly well suited for use as a chemical feed pump because of such characteristics, is obviously susceptible of many other diversified and advantageous applications.

I claim:

1. In a variable rate feeding mechanism, a reciprocating pump, means for operating the pump at a constant speed, means including a cam for limiting the stroke of the pump, and means for automatically adjusting said

limiting means while the pump is in operation to vary the rate of flow.

2. In a variable rate feeding mechanism, a reciprocating pump, means for operating the pump at a constant speed, a rotatable cam for limiting the stroke of the pump in one direction without limiting it in the other, and a float control means for automatically rotating the cam while the pump is in operation, whereby to vary the rate of flow. 70

3. In a variable rate feeding mechanism, a reciprocating pump, means for operating the pump, a rotatably mounted cam for limiting the stroke of the pump, and means for rotating the cam while the pump is in operation, whereby to vary the rate of flow. 80

4. In a variable rate feeding mechanism, a pump having a plunger, a cross head connected with the plunger, power operated means for moving the cross head in one direction, spring means for moving the cross head in the opposite direction, an adjustably positioned stop for limiting the movement of the cross head in the direction in which it is moved by said spring means, and means for adjusting the position of the stop while the pump is in operation, whereby to vary the rate of flow. 85

5. In a variable rate feeding mechanism, a pump having a plunger, a cross head connected with the plunger, a motor, a shaft, a power-transmitting connection between the motor and the shaft, an eccentric on one end of the shaft which engages with the cross head and moves it in one direction, a spring which engages with the cross head and moves it in the opposite direction, a rotatably mounted cam which engages with the cross head and limits the extent to which it is moved under the action of the spring, and means for rotating the cam, whereby to vary the rate of flow. 90 95

6. In a variable rate feeding mechanism, a pump having a plunger, a cross head connected with the plunger, a motor, a shaft, reduction gearing connecting the shaft with the motor, an eccentric on one end of the shaft which engages with the cross head and moves it in one direction, springs which engage with the cross head and move it in the opposite direction, a rotatably mounted cam which engages with the cross head and limits the extent to which it is moved under the action of the springs, and means for rotating the cam, whereby to vary the rate of flow. 100 105 110

7. In a variable rate feeding mechanism, a reciprocating pump, means for operating the pump at a constant speed, means for limiting the stroke of the pump, means for indicating the rate of flow in an associated apparatus, and means operatively connected with said indicating means for adjusting said limiting means to maintain the flow through the pump in direct proportion to the 115 120 125 130

flow in the associated apparatus regardless of changes occurring in the latter.

8. In water softening apparatus, means for indicating the rate of flow of the water being treated, a reciprocating pump for effecting a flow of the chemicals to the water, means for operating the pump at a constant speed, means for limiting the stroke of the pump, and means actuated by said indicating means for adjusting said limiting means whereby to vary the rate of flow of the chemical in conformity with variations in the rate of flow of the water to maintain a constant proportion therebetween.
- 15 9. In a variable rate feeding mechanism, a reciprocating pump, means for operating the pump, means for changing the stroke of the pump to increase or decrease the rate of flow through the same, and means for automatically compensating for leakage through the pump at any particular length of stroke.

In testimony whereof I have hereunto subscribed my name.

ALBERT B. HODGES.
